TRAVELING ADVERTISING SIGN

Application filed May 20, 1931. Serial No. 538,651.

My present invention relates to advertising devices and more particularly to devices of general character specified, as are commonly known as "reflector signs." It is an object of the present invention to provide a movable or traveling daylight sign which is simple in construction, easy and economical to fabricate and assemble, and which performs the intended functions in an exceedingly admirable manner.

In the accompanying specification, I shall describe, and in the annexed drawings show, an illustrative embodiment of the advertising device of the present invention. It is, however, to be clearly understood that the present invention is not limited to the aforesaid illustrative embodiment of the same, which is herein described and shown for purposes of illustration only.

In the accompanying drawings, Fig. 1 is a top plan view of the aforesaid illustrative embodiment of the present invention, the casting thereof being removed to show the internal construction.

Fig. 2 is a longitudinal sectional view taken on line 2—2 of Fig. 1.

Fig. 3 is a transverse sectional view taken on line 3—3 of Fig. 2.

Fig. 4 is an end view of the aforesaid illustrative embodiment of the present invention, here again the cover being removed; and

Fig. 5 is an enlarged detailed, longitudinal sectional view of one of the idlers employed in the aforesaid illustrative embodiment of the present invention.

Referring now more in detail to the aforesaid illustrative embodiment of the moving or traveling signs of the present invention, and with particular reference to the drawings illustrating the same, numeral 10 generally indicates a sign made in accordance with the aforesaid illustrative embodiment of the present invention. Such sign includes the rectangular base plate 11 provided at the four edges thereof with the upstanding flanges 12. The base plate 11 is spot-welded to a dish-shaped bezel or frame 13 and is provided with a plurality, here shown as four, feet 14. Secured to the base plate 11 near the short, end edges thereof, is a pair of U-shaped brackets

15 and 16. Each of the brackets consists of a rear vertical portion 17, an upper leg 18, and a lower leg 19, the brackets being secured to the base plate by spot-welding the lower legs 19 to the base plate. Secured intermediate the upper and lower legs 18 and 19 of the bracket 16, is another U-shaped bracket 20, this bracket consisting of the front vertical portion 21, the lower leg 22, which is spot-welded to the lower leg 19 of the bracket 16, and the upper leg 23 which is spot-welded to the upper leg 18 of the bracket 16. Secured to the upper leg 18 of the U-shaped bracket 15, as by having the upper horizontal portion 24 thereof spot-welded to the same, is an angle iron 25, the front vertical portion 26 of which is provided at the lower end thereof with the offset portion 26', the latter portion being spot-welded to a horizontally extending arm 27 of a vertical bracket 28, the leg portion 29 of which is spot-welded to the base plate 11 near the end opposite to that which supports the bracket 16.

Formed with the front portions 26 and 21 of the brackets 25 and 20, are forwardly extending plates 30 and 31, which are adapted to carry, respectively, angle irons 32 and 33. The angle irons are provided with the obliquely disposed supporting portions 34 and 35, these portions being disposed, normally at an angle of 45° to the base plate 11. The angle irons 32 and 33 are secured to the plates 30 and 31 by being pivotally attached thereto by the bolts 36, the angle irons being also provided with elongated slots 37, through which pass bolts 38, engageable in the plates 30 and 31, and held in place by nuts 39, the arrangement being such that the angle irons 32 and 33, can be altered as conditions require. The supporting portions 34 and 35 of the angle irons 32 and 33, have at their lower front edges, U-shaped holders 40 and 41 adapted to receive a mirror 42. Thus, any images reflected in the mirror from above the same, may be seen by an observer standing in the front of the advertising device of the present invention.

The numeral 43 generally designates film tracks, which consist of L-shaped runners 44 and 45, secured to the upper surfaces of the

upper legs 18 of the brackets 15 and 16. The runners 44 and 45, consist of the horizontal portions 46 and 47, and the vertical portions 48 and 49.

5 The entire device is enclosed in a casing 50 which consists of the rear wall 51, end walls 52 and 53, front wall 54 and top wall 55. The front wall 54 is provided with the rectangular opening 56 through which the reflections in the mirror 42 may be observed, and the edges surrounding the opening 56 are bent upon themselves at 57 so as to reinforce the opening.

15 The lower edges of the rear, side and front walls, are bent inwardly, to present flanges 58 by means of which the casing 50 rests upon the base plate 11 within the upstanding flanges 12.

20 The top wall 55 of the casing 50 is also provided with a rectangular opening 59, this opening being surrounded by downwardly directed flanges 60 which fit within the vertical portions 48 and 49 of the runners 44 and 45. The purpose of this arrangement 25 is to keep the runners uniformly spread apart throughout their length, so as not to interfere with the proper movement of the film which they guide, as will be readily understood as this description progresses. Internally formed with the downwardly directed flanges 60 are inwardly directed flanges 61, the lower surfaces of which are adapted to cooperate with the horizontal portions 46 and 47, of the runners 44 and 45, so as to 30 guide the marginal portions of the film 62, which passes intermediate the horizontal portions 46 and 47 of the runners 44 and 45, and the inwardly directed flanges 61 of the downwardly directed flanges 60 which surround the opening 59 in the upper wall 55 of the casing 50. The upper surface of the flanges 61 and the facing surfaces of the flanges 60 are receptive of a rectangular sheet 63 of flashed opal or other translucent glass, the 35 arrangement being such, that the upper surface of the glass is flush with the upper surface of the top wall 55.

40 The film 62 is run about a series of rollers 64. The film also passes about a roller 65 and another roller 66, all as clearly shown in Fig. 2 of the drawings. The roller 65 is carried by the vertical bracket 28, and the roller 66 is carried by a bracket 67 slidable along a horizontal bar 68 carried by the 45 brackets 28 and 20. The position of the bracket 67 may be adjusted, and after adjusted retained in place by means of a set screw 69, the purpose of this roller being to take up any slack which there may be in the film 62. Each of the rollers 64, 65 and 66 50 preferably consists of a cylindrical wooden body 70 having enlarged end portions 71 and is provided with the end bores 72 connected by the counter bore 73 of lesser diameter. 55 The bores 72 are receptive of inserts 74 and

75 of Arguto wood, these inserts constituting oilless bearings, by means of which the rollers may be rotatably mounted on the pins 76 having the heads 77. Intermediate the outer end of each of the rollers and the head 77 73 of its pin 76, is a washer 78, the opposite end of the pin being threaded at 79 so that the rollers may be secured to their supports as set forth in earlier portions of this specification. The film 62 contacts only the enlarged 75 portions 71 of each of the rollers at the marginal portions thereof, so that those portions of the film that contain written matter do not come in contact with any portion of the rollers, thus giving longer life to the 80 same.

85 In order that the film, which is endless, be moved continuously, I provided driving means 80. Such driving means preferably consists of an electric motor 81 of approximately one-fiftieth of a horse-power, which motor is adapted, through a right-angle drive 82 to rotate a shaft 83. This shaft has fixed thereon a large rubber roller 84 adapted to cooperate with a smaller rubber roller 85 to 90 frictionally engage therebetween the film 62. The smaller rubber roller 85 is journaled in a bracket 86 carried on a resilient arm 87 extending downwardly from the forwardly directed extension 88 of the arm 27 of the 95 bracket 28.

99 The speed of the motor 81 may be controlled by means of a rheostat 89 mounted upon the base plate 11 and having a control handle 90 adapted to be operated in a horizontal plane and passing out of the casing 50 through a slot 91 in the rear wall 51. Adjacent the rheostat 89 I provide a bracket 92, which is adapted to support an electrical receptacle 93, the latter being secured to the bracket by a strap 94, and extending beyond the rear wall 51 of the casing 50 through an opening 95.

110 All of the various electrical portions of the present invention may be wired as follows: One terminal of the receptacle 93 is connected by a wire 96 to one terminal of the motor 81. The other terminal of the motor 81 is connected by a wire 97 to one terminal 98 of the rheostat 89; and the other terminal 99 of the rheostat is connected by a wire 100 to the remaining terminal of the receptacle 93.

115 If it is found desirable, the opening 56 in the front wall 54 of the casing 50 may be closed by means of a glass window 101 so as to make the casing as a whole dust-proof. If the window 101 is employed, there may be slot-welded to the rear surface of the front wall 101, immediately below the lower longitudinal bend 57 surrounding the opening 56, the Z-shaped bracket 102 which is receptive of the lower edge of the glass, the upper edge of the glass being retained against the upper longitudinal bend 57 surrounding the opening 56 by a series of clips 103.

This completes the description of the construction of the aforesaid illustrative embodiment of the advertising devices of the present invention. It is believed that the mode of operation thereof will be readily apparent to those skilled in the art to which the present invention relates, but for the sake of clarity, the operation may be briefly summarized as follows:

10 After the device 10 has been permanently settled in the position that it is intended that it occupy, the mirror 42 is adjusted, as above described, so that the reflections therein, coming from above the same, will be readily seen by persons standing in front of the device. The electric current is then applied so as to operate the motor 81 which, through the cooperating rubber rollers 84 and 85, which engage therebetween the film 62, will drive 15 the film in the circuitous path indicated in Fig. 2 of the drawings. As the film passes beneath the flashed opal glass 63, with the marginal portions thereof guided intermediate the runners 44 and 45, and the flanges 20 61, any light entering the casing 50 will pass through the glass 63 and film 62, to create images of the inscriptions of the film in the mirror 42, and these reflections will be readily observed by persons standing in front of or 25 at an angle to the sign through the opening 56 in the front wall 54 of the casing 50. Should there be too much slack in the film, the same may be taken up by loosening the 30 set screw 69 and moving the bracket 67 to the left in Fig. 2, until the slack is taken up, after which the set screw 69 may again be tightened.

This completes the description of the operation of the advertising devices of the present 40 invention. It will be noted that such devices are simple in construction, contain few operative parts, are easy and economical to fabricate and assemble, and provide excellent advertising facilities at low cost and with considerable effectiveness. Other superiorities 45 and advantages of the devices of the present invention will be readily apparent to those skilled in the art to which the present invention relates.

50 What I claim as my invention is:

1. In a traveling sign, a base plate, a plurality of end supporting members carried thereby, and a mirror-supporting member carried by each of said end supporting members, each of said mirror-supporting members being provided with an inclined mirror-supporting surface, together with means for adjusting the inclination of said mirror-supporting members, together with a plurality 55 of longitudinally disposed flanged guide members carried by said end supporting members, an endless flexible sign stencil having a portion thereof passing over said longitudinally disposed flanged guide members, a plurality of rollers for carrying said endless 60 flexible sign stencil, means for moving said endless flexible sign stencil over said rollers at an adjustable rate of speed and means for tensioning said endless flexible sign stencil in its movement over said flanged guide members, in combination with a closure adapted to cover and house the operating parts of the sign carried by said base plate, said closure embodying a top portion carrying a glass 65 member.

flexible sign stencil, means for moving said endless flexible sign stencil over said rollers at an adjustable rate of speed and means for tensioning said endless flexible sign stencil in its movement over said flanged guide members, in combination with a closure adapted to cover and house the operating parts of the sign carried by said base plate, said closure embodying a top portion carrying a glass member.

2. In a traveling sign, a base plate, a plurality of end supporting members carried thereby, and a mirror-supporting member carried by each of said end supporting members, each of said mirror-supporting members being provided with an inclined mirror-supporting surface, together with means for adjusting the inclination of said mirror-supporting members, together with a plurality of longitudinally disposed flanged guide members, a plurality of rollers for carrying said endless flexible sign stencil, means for moving said endless flexible sign stencil over said rollers at an adjustable rate of speed and means for tensioning said endless flexible sign stencil in its movement over said flanged guide members, in combination with a closure adapted to cover and house the operating parts of the sign carried by said base plate, said closure embodying a top portion carrying a glass member and having also a front member provided with an opening therein and a transparent glass member carried in said opening.

3. In a traveling sign, a base plate, a plurality of end supporting members carried thereby, and a mirror supporting member carried by each of said end supporting members, each of said mirror-supporting members being provided with an inclined mirror-supporting surface, together with means for adjusting the inclination of said mirror-supporting members, together with a plurality of longitudinally disposed flanged guide members carried by said end supporting members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed and means for tensioning said endless flexible sign stencil in its movement over said flanged guide members, in combination with a closure adapted to cover and house the operating parts of the sign carried by said base plate, said closure embodying a top portion having a cutaway portion provided with a plurality of opposed, depending flange portions carrying a glass member and having also a front

member provided with an opening therein and a transparent glass member carried in said opening.

4. In a traveling sign, a base plate, a plurality of end supporting members carried thereby, and a mirror-supporting member carried by each of said end supporting members, each of said mirror-supporting members being provided with an inclined mirror-supporting surface, together with means for adjusting the inclination of said mirror-supporting members, together with a plurality of longitudinally disposed flanged guide members carried by said end supporting members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed and means for tensioning said endless flexible sign stencil in its movement over said flanged guide members, in combination with a closure adapted to cover and house the operating parts of the sign carried by said base plate, said closure embodying a top portion having a cutaway portion provided with a plurality of opposed, depending flange portions carrying a glass member.

5. In a traveling sign, a base plate, a plurality of end-supporting members carried thereby, and a mirror-supporting member carried by each of said end-supporting members, each of said mirror-supporting members being provided with an inclined mirror-supporting surface, together with means for adjusting the inclination of said mirror-supporting members, together with a plurality of longitudinally disposed flanged guide members carried by said end-supporting members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed, and means for tensioning said endless flexible sign stencil in its movement over said flanged guide members, by the adjustment of one of said rollers, in combination with a closure adapted to cover and house the operating parts of the sign carried by said base plate, said closure embodying a top portion carrying a glass member.

60 6. In a traveling sign, a base plate, a plurality of end-supporting members carried thereby, and a mirror supporting member carried by each of said end supporting members, each of said mirror-supporting members being provided with an inclined mirror-supporting surface, together with means for adjusting the inclination of said mirror-supporting members, together with a plurality of

longitudinally disposed flanged guide members carried by said end supporting members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed, and means for tensioning said endless flexible sign stencil in its movement over said flanged guide members, by the adjustment of one of said rollers, in combination with a closure adapted to cover and house the operating parts of the sign carried by said base plate, said closure embodying a top portion carrying a glass member, and having also a front member provided with an opening therein and a transparent glass member carried in said opening.

7. In a traveling sign, a base plate, a plurality of end supporting members carried thereby, and a mirror-supporting member carried by each of said end-supporting members, each of said mirror-supporting members being provided with an inclined mirror-supporting surface, together with means for adjusting the inclination of said mirror-supporting members, together with a plurality of longitudinally disposed flanged guide members carried by said end supporting members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed, and means for tensioning said endless flexible sign stencil in its movement over said flanged guide members by the adjustment of one of said rollers, in combination with a closure adapted to cover and house the operating parts of the sign carried by said base plate, said closure embodying a top portion having a cutaway portion provided with a plurality of opposed, depending flange portions carrying a glass member and having also a front member provided with an opening therein and a transparent glass member carried in said opening. 110

8. In a traveling sign, a base plate, a plurality of end supporting members carried thereby, and a mirror-supporting member carried by each of said end supporting members, each of said mirror-supporting members being provided with an inclined mirror-supporting surface, together with means for adjusting the inclination of said mirror-supporting members, together with a plurality of longitudinally disposed flanged guide members carried by said end supporting members, an endless flexible sign stencil having a portion thereof passing over said longitudinally disposed flanged guide members, a plurality of rollers for carrying said end- 125 130

less flexible sign stencil, means for moving said endless flexible sign stencil over said rollers at an adjustable rate of speed, and means for tensioning said endless flexible sign stencil in its movement over said flanged guide members by the adjustment of one of said rollers in combination with a closure adapted to cover and house the operating parts of the sign carried by said base plate, 60 said closure embodying a top portion having a cutaway portion provided with a plurality of opposed, depending flange portions carrying a glass member.

9. In a traveling sign, a base plate, a plurality of end-supporting members carried thereby, and a mirror-supporting member carried by each of said end-supporting members, each of said mirror-supporting members being provided with an inclined mirror 15 supporting surface, together with means for adjusting the inclination of said mirror-supporting members, together with a plurality of longitudinally disposed flanged guide members carried by said end-supporting 20 members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed, and means for tensioning said endless flexible sign stencil in its movement over said flanged guide members, by the adjustment by one of 25 said rollers, in combination with a closure adapted to cover and house the operating parts of the sign carried by said base plate, said closure embodying a top portion carrying a glass member, and an aperture for 30 the passage therethrough of a rheostat-operating member for regulating the speed of the moving means.

10. In a traveling sign, a base plate, a plurality of end-supporting members carried thereby, and a mirror-supporting member carried by each of said end-supporting members, each of said mirror-supporting members being provided with an inclined mirror-supporting surface, together with means for 45 adjusting the inclination of said mirror-supporting members, together with a plurality of longitudinally disposed flanged guide members carried by said end-supporting members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed, and means for tensioning said endless flexible sign stencil in its movement over said flanged guide members, by the adjustment of one of said rollers, in combination with a closure adapted 60 to cover and house the operating parts of 65

the sign carried by said base plate, said closure embodying a top portion carrying a glass member, and having also a front member provided with an opening therein and a transparent glass member carried in said opening, and an aperture for the passage therethrough of a rheostat-operating member for regulating the speed of the moving means. 70

11. In a traveling sign, a base plate, a plurality of end-supporting members carried thereby, and a mirror-supporting member carried by each of said end-supporting members, each of said mirror-supporting members being provided with an inclined mirror-supporting surface, together with means for adjusting the inclination of said mirror-supporting members, together with a plurality of longitudinally disposed flanged guide members carried by said end supporting members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed, and means for tensioning said endless flexible sign stencil in its movement over said flanged guide members by the adjustment of one of said rollers, in combination with a closure adapted to cover and house the operating parts of the sign carried by said base plate, said closure embodying a top portion having a cutaway portion provided with a plurality of opposed, depending flange portions carrying a glass member and having also a front member provided with an opening therein and a transparent glass member carried in said opening, and an aperture for the passage therethrough of a rheostat-operating member for regulating the speed of the moving means. 90

12. In a traveling sign, a base plate, a plurality of end-supporting members carried thereby, and a mirror-supporting member carried by each of said end-supporting members, each of said mirror-supporting members being provided with an inclined mirror-supporting surface, together with means for adjusting the inclination of said mirror-supporting members, together with a plurality of longitudinally disposed flanged guide members carried by said end-supporting members, an endless flexible sign stencil having a portion thereof passing over said longitudinally disposed flanged guide members, a plurality of rollers for carrying said endless flexible sign stencil, means for moving said endless flexible sign stencil over said rollers at an adjustable rate of speed, and means for tensioning said endless flexible sign stencil in its movement over said flanged guide members by the adjustment of one of said rollers in combination with a closure adapted to cover and house the operating 100 105 110 115 120 125 130

parts of the sign carried by said base plate,
said closure embodying a top portion having
a cutaway portion provided with a plurality
of opposed, depending flange portions carry-
5 ing a glass member, and an aperture for the
passage therethrough of a rheostat-operating
member for regulating the speed of the mov-
ing means.

In testimony, whereof, I have signed my
10 name to this specification this 15th day of
May, 1931.

MORRIS J. COHAN.
